UNITED STATES PATENT OFFICE.

EDWARD J. McCORMACK, OF SAN FRANCISCO, CALIFORNIA.

COLLAPSIBLE ELECTRIC HEATER.

Application filed July 13, 1921. Serial No. 484,391.

To all whom it may concern:

Be it known that I, EDWARD J. McCORMACK, a citizen of the United States, residing in the city and county of San Francisco and State of California, have invented a new and useful Improvement in a Collapsible Electric Heater, of which the following is a specification.

My invention relates to improvements in electric heaters wherein a collapsible reflector and guard is provided to enclose a heating element.

The primary object of my invention is to provide an improved electric heating device provided with a collapsible reflector to permit packing within a small space.

Another object is to provide a heater arranged to be supported in a horizontal or vertical position.

20 A further object is to provide an improved collapsible guard arranged to be folded within a reflector.

25 A further object is to provide improved means for retaining a collapsible reflector and guard in an extended or folded position.

A still further object is to provide a heater arranged to be supported in a horizontal plane and having an improved guard arranged to support a vessel to be heated 30 above the heating element.

A still further object is to provide a collapsible reflector arranged to enclose the heating element to protect said element when folded.

35 I accomplish these and other objects by means of the improved device disclosed in the drawings forming a part of the present specification wherein like characters of reference are used to designate similar parts 40 throughout said specification and drawings, and in which:

Fig. 1 is a front elevation of my improved heating device, one-half of the reflector and guard being shown in the extended position and the other half shown in folded position.

Fig. 2 is a transverse section through the device shown in Fig. 1, in extended position.

Fig. 3 is a similar section with the reflector and guard in the folded position.

Fig. 4 is a broken detail showing the manner of hinging the sectors to the base.

The numeral 1 is used to designate an electrical heating element mounted upon a base plate 2 secured upon a standard 3. A suit-

able clamp 4, adapted for engagement with any external object, is pivotally connected to the standard 3 and is arranged to be held at any desired inclination thereto by a wing nut 6. In the drawings I have illustrated a spring clamp 4 having a relatively wide range of expansion and operated by a wing nut 6 to permit the clamp to be rigidly mounted upon any convenient object. The element 1 is connected to a source of electrical energy, not shown, by a connection 8.

A plurality of radial sectors 9 are connected to the base plate 2, by means of suitable hinges 11 arranged tangentially to the periphery of the plate 2 as shown 70 in Fig. 4 of the drawings, to form a reflector, portions of said plate 2 being bent to form butts for the hinges 11 as best shown in Fig. 4 of the drawings. Stay wires 12 are pivotally connected to the 75 outer edges of the sectors 9 and to a centrally disposed ring 14, which is movable axially into and away from the reflector. When in the extended position the stays 12 retain the sectors 9 in position and form a 80 guard in front of the element 1.

Spring clips 16 secured to the plate 2 extend outwardly from the reflector, the outer end of each clip being bent to form a shoulder 17 arranged to engage the ring 14 85 when moved outwardly to the extended position as best disclosed in Fig. 2 of the drawings. The ends 18 of the clips 16 are bent to limit the outward movement of the ring. Shoulders 19 are formed near the 90 inner ends of the clips 16 to engage the ring 14 when moved inwardly to the folded position shown in Fig. 3 of the drawings.

The sectors 9 are widened at their outer ends, the wide part of each sector 9 being arranged to overlap the sector adjacent thereto upon one side, and to be overlapped by the adjacent sector upon the other side, in this manner forming a solid reflecting surface. The stays 12 are arranged to move 100 the sectors 9 outwardly so that the overlapping edges will be in close contact and each sector will serve to limit the movement of the adjacent sector.

When it is desired to extend the reflector 105 into an operative position, the sectors 9 are moved outwardly and the ring 14 moved into engagement with the shoulder 17, the stays 12 being thereby moved to lie in a plane defined by the outer edge of the reflector and 110

the ring, and form a flat rigid guard in front of the element 1. With the reflector extended in this position it may be adjusted at any inclination by the pivot bearing 5 of the standard 3 and the wing nut 6 to direct heat from the element 1 in any desired direction. If it is desired to utilize the heat for cooking purposes, the reflector may be turned to a horizontal position as shown 10 in dotted lines in Fig. 2 of the drawings. The guard formed by the stays 12 may now be utilized for supporting a vessel, outward movement of the sectors 9 being prevented by the stays 12, and movement of the ring 14 and the stays 12 into the reflector being prevented by the clips 16. Heat from the element 1 will be thrown directly upon the vessel and the contents quickly heated.

When it is desired to fold the reflector, 20 the ends 18 of the clips 16 are pressed inwardly to cause the shoulders 17 to release the ring 14. The ring 14 may now be moved inwardly into the reflector thereby permitting the stays 12 and the sectors 9 to be 25 moved into the position shown in Fig. 3 of the drawing. As the sectors 9 are pressed together the ring 14 will be pressed back over the clips 16 to its innermost position where it is engaged by the shoulders 19.

30 As it is necessary for the ring 16 to move outwardly from the reflector when the sectors 9 are moved to the extended position, the shoulders 19 will normally prevent opening of the reflector until the outer ends are 35 forced outwardly by an operator against the pressure of the clips 16 to move the ring past the shoulders 19.

From the above description it will be 40 readily seen that I have provided an improved heating device which may be folded to occupy a minimum space which may be utilized for either heating a room or for cooking purposes. The device is particularly useful while travelling as it may be 45 folded and readily packed in small space in a trunk or suitcase, where it will be readily accessible for heating a room, for heating water, or for doing light cooking. While I have shown the preferred form of my invention only, the details of construction are 50 subject to various modifications without departing from the spirit of my invention.

Having thus described my invention what I claim as new and desire to secure by Letters Patent is:

1. A folding electrical heater comprising a heating element; a collapsible reflector connected to said element; and means for normally retaining said reflector in an extended or folded position.

2. A folding electrical heater comprising a heating element; a collapsible reflector connected to said element; means for normally retaining said reflector in an extended or folded position; and means for retain-

ing said reflector in a vertical position for heating or a horizontal position for cooking purposes.

3. A folding electrical heater comprising a heating element; a collapsible reflector connected to said element; means for normally retaining said reflector in an extended or folded position; and a suitable clamp pivotally connected to said heater and adapted for engagement with an article for retaining the heater in a vertical or horizontal position.

4. A folding electrical heater comprising a heating element; a collapsible reflector comprising radial collapsible sectors hingedly connected to said heater; a collapsible wire guard pivotally connected to said heater and sectors and arranged to be folded and extended with said sectors; and means for normally retaining said sectors and wire guard in an extended position.

5. A folding electrical heater comprising a heating element; a collapsible reflector comprising radial collapsible sectors hingedly connected to said heater; a collapsible wire guard pivotally connected to said heater and sectors and arranged to be folded and extended with said sectors; and means for normally retaining said sectors and wire guard in an extended or folded position; and means for retaining said reflector in a vertical position for heating or a horizontal position for cooking purposes.

6. A folding electrical heater comprising a heating element; a collapsible reflector comprising a plurality of radial sectors hingedly connected to said heater; a collapsible guard, said guard comprising a centrally disposed ring, and a plurality of stays pivotally connected between the ring and each sector and arranged to be folded and extended with said sectors; and means for retaining said sectors and guard in an extended or folded position.

7. A folding electrical heater comprising a base plate; a heating element mounted upon said plate; a collapsible reflector comprising a plurality of radial sectors hingedly connected to the periphery of the base plate; a collapsible guard, said guard comprising a centrally disposed ring, and a plurality of stays pivotally connected between the ring and each sector, and arranged to be folded and extended with said sectors; and means for retaining said sectors and guard in an extended or folded position.

8. A folding electrical heater comprising a base plate; a heating element mounted upon said plate; a collapsible reflector comprising a plurality of radial sectors hingedly connected to said base plate tangentially to the periphery thereof; a collapsible guard comprising a centrally disposed ring, and a plurality of stays pivotally connected between the ring and each sector and ar-

ranged to be folded and extended with said sectors; and means for retaining said sectors and guard in extended or folded position.

- 5 9. A folding electrical heater comprising a base plate; a heating element mounted upon said plate; a collapsible reflector comprising a plurality of radial sectors hingedly connected to said base plate tangentially to the periphery thereof; a collapsible guard comprising a centrally disposed ring, and a plurality of stays pivotally connected between the ring and each sector; arranged to be folded and extended with said sectors; 15 means for retaining said sectors and guard in extended or folded position; and means for retaining said reflector in a vertical position for heating or in a horizontal position for cooking purposes.

- 20 10. In a heating device, a collapsible reflector comprising a plurality of radial sectors hingedly connected to enclose a heating element.

- 25 11. In a heating device a collapsible reflector comprising a plurality of overlapping radial sectors hingedly connected to enclose a heating element.

- 30 12. In a heating device: a collapsible reflector comprising a plurality of radial sectors hingedly connected to said device; and a collapsible guard comprising a centrally disposed ring and a plurality of stays pivotally connected between said ring and the sectors and arranged to be enclosed within 35 the reflector when collapsed.

- 35 13. In a heating device of the character described having a collapsible reflector; a guard comprising a centrally disposed ring, and a plurality of stays pivotally mounted between the ring and the reflector to permit axial movement of said ring toward and away from the reflector, for folding and extending said reflector and guard.

- 40 14. In a heating device of the character described having a collapsible reflector; a

guard comprising a centrally disposed ring, and a plurality of stays pivotally mounted between said ring and the reflector to permit axial movement of said ring toward and away from the reflector for folding and extending said reflector and guard; and spring clips mounted within the reflector and provided with shoulders at the inner and outer ends to engage the ring and hold the same in an extended or folded position. 50 55

15. A folding heater comprising a heating element; a collapsible reflector hingedly connected to said heater; a collapsible guard, said guard comprising a centrally disposed ring and a plurality of stays pivotally connected between the ring and the sectors to permit axial movement of said ring into and away from the reflector for holding and extending said reflector and guard; spring clips mounted upon the heater within the reflector, said clips being provided with shoulders at the inner and outer ends thereof to engage the ring and hold the same in an extended or folded position. 60 65

16. A folding heater comprising a heating element; a collapsible reflector hingedly connected to said heater; a collapsible guard, said guard comprising a centrally disposed ring and a plurality of stays pivotally connected between the ring and the sectors to permit axial movement of said ring into and away from the reflector for holding and extending said reflector and guard; spring clips mounted upon the heater within the reflector, said clips being provided with shoulders at the inner and outer ends thereof to engage the ring and hold the same in an extended or folded position; and a suitable clamp pivotally connected to the heater and adapted for engagement with an external object to permit adjustment of the inclination of the reflector. 70 75 80 85

In witness whereof I hereunto set my signature.

EDWARD J. McCORMACK.
